UNITED STATES PATENT OFFICE.

DAVID GRATTAN, OF ANACONDA, MONTANA.

NOZZLE-TIP FOR LOCOMOTIVES.

SPECIFICATION forming part of Letters Patent No. 717,986, dated January 6, 1903.

Application filed June 18, 1902. Serial No. 112,253. (No model.)

To all whom it may concern:

Be it known that I, DAVID GRATTAN, a citizen of the United States, and a resident of Anaconda, in the county of Deerlodge and State of Montana, have made certain new and useful Improvements in Nozzle-Tips for Locomotives, of which the following is a specification.

My invention is an improvement in exhaust-nozzles for locomotives, and has for an object 10 to provide a novel construction of nozzle-tip, to which end the invention consists in certain novel constructions and combinations of parts, as will be hereinafter described and claimed.

15 In the drawings, Figure 1 is a vertical cross-section of the nozzle-tip as in use. Fig. 2 is a detail perspective view of the nozzle-tip. Fig. 3 is a top plan view of the nozzle-tip, and Fig. 4 is an enlarged section thereof, and Fig. 20 5 is a detail section through one of the bridge-strips for supporting the inverted cone.

The nozzle-tip is secured to the exhaust-pipe or nozzle-stand A, preferably by fitting the tubular body B of the tip in the upper 25 end of the stand and securing it by means of the screws C, which enter a groove B', formed in the outer side of the body B, near the lower end thereof. This groove B' extends entirely around the body B for convenience in securing 30 the tip in position, and when entered by the screws C the latter will secure the tip in position as desired. The body B is provided externally at its upper end with a circumferential outwardly-projecting flange B², which 35 rests upon the upper end of the nozzle-stand A and aids in securing the desired joint between the parts A and B.

In its general construction my nozzle-tip tapers inwardly from the bottom and flares at 40 the top. This is secured by means of the inwardly-tapering form of the bore or inner surface B³ of the body B, which converges toward the top of the tube B, as shown in Figs. 1 and 4, and by means of the inverted cone 45 or spreader D, supported above the tube B and concentrically therewith, as shown in Figs. 1 and 4. It will be noticed the body B tapers inwardly toward its top, while the inverted cone flares outwardly on its sides, thus 50 securing the desired taper of the tip from its bottom and the flaring construction at the top. The cone D is supported by means of

the bridge-strips E, which are tapered downwardly in cross-section and present at their lower sides approximately cutting edges in 55 order to offer the least obstruction to the discharge from the nozzle. It will be noticed the apex of the inverted cone projects slightly below the lower cutting edges of the bridge-strips, the sides of the cone and the inner 60 ends of the bridge-strips merging, as will be understood from Figs. 2 and 4. It will be noticed that the bridge-strips lie partly above the top of the body B and that the inverted cone extends above the said body B, so that 65 the outward tendency given the exhaust by the said cone is imparted thereto subsequent to the condensing tendency effected by the inward taper of the bore of the body B, so that the cone will operate upon the condensed 70 exhaust in such manner as to fill the stack with exhaust-steam, as desired.

In practice the tip may be made in different sizes in order to fit the different nozzle-stands in the various types of locomotives. 75

In operation the tapering plan of the shell or body B, with the aid of the V-shaped bridge-strips and the inverted cone arranged and operating as described, provides a greater area than is secured by the ordinary tip, and consequently the stack is filled at all points with exhaust-steam, thus removing the back pressure on the piston-head, greatly reducing the consumption of fuel, increasing the power of freight and switching locomotives, and increasing the speed of passenger-locomotives by permitting the steam to escape freely to the atmosphere the instant release takes place from the cylinder. 85

The device is simple and can be applied to 90 a locomotive at a small cost and without any loss of time.

The invention results in use in a saving on the flues, as by means of my improved nozzle-tip the draft on the fire is even and there are 95 no holes in the fire allowing the cold air to come up and strike the flues.

Having thus described my invention, what I claim as new, and desire to secure by Letters Patent, is—

1. The nozzle-stand combined with the nozzle-tip having the body portion or shell tapered inwardly toward its upper end and provided externally at its upper end with a flange

- to rest upon the nozzle-stand and in its outer side near its lower end with the circumferential groove to receive the screws for securing the tip in the nozzle-stand, the said screws, 5 the bridge-strips extending across the upper end of the shell and tapering downwardly in cross-section, and the inverted cone supported by said bridge-strips concentrically with the said shell or body and extending above 10 the shell or body substantially as and for the purposes set forth.
2. The nozzle-tip comprising the body or shell having its bore tapered inwardly toward its upper end, and the inverted cone supported above the body or shell and concentric therewith substantially as set forth. 15
3. A nozzle-tip comprising the body or shell having its bore tapered inwardly toward its upper end and provided in its outer side with 20 a circumferential groove and at its upper end with an outwardly - projecting flange, the bridge-strips supported on and extending across the upper end of the body or shell, and the inverted cone supported by said bridge- 25 strips above the body or shell and concentric therewith substantially as set forth.

4. A nozzle-tip substantially as herein described comprising the body or shell, the bridge-strips, and the inverted cone supported by the bridge-strips above the upper end 30 of the body or shell substantially as set forth.

5. A nozzle-tip for locomotives comprising the body or shell, the inverted cone concentric with said shell and the bridge-strips connecting the cone and shell and projecting above the upper edge of the shell, whereby 35 to support the cone, and to aid in spreading the exhaust as it emerges from the shell substantially as set forth.

6. A nozzle-tip for locomotives comprising 40 the body or shell tapering inwardly from the bottom and flaring outwardly at the top, the inverted cone, and the bridge-strips connecting the shell and cone and projecting above the upper edge of the shell and tapered in 45 cross-section, all substantially as and for the purposes set forth.
